UNITED STATES PATENT OFFICE.

CHARLES R. C. BORDEN, OF BROOKLINE, MASSACHUSETTS.

HEADLIGHT.

1,188,240.

Specification of Letters Patent. Patented June 20, 1916.

Application filed November 1, 1915. Serial No. 58,953.

To all whom it may concern:

Be it known that I, CHARLES R. C. BORDEN, a citizen of the United States, residing at Brookline, county of Norfolk, Commonwealth of Massachusetts, have invented certain new and useful Improvements in Headlights, of which the following is a specification.

This invention relates to automobile headlight devices and particularly to a headlight capable of a vertical droop or depression of its focal axis in order to avoid the glare upon an approaching driver although maintaining at the same time a suitable illumination of the intervening space.

The danger from the overpowering effect of a powerful headlight on the eyes of an approaching driver is well recognized. The frequency of collisions or other accidents from the temporary blinding of a driver by an approaching light are common.

In my present invention, I provide for the drooping of the axis of illumination so that the zone of intense illumination is brought below the level of the usual plane and at the same time I provide for shifting the focus so that the illumination of the preceding space is made possible under suitable conditions of driving.

I am well aware that dirigible headlights so called have been provided, particularly with reference to the turning movement of the car in rounding a curve. I am also aware that headlights have been provided which might be steered or directed in any direction. The present invention however involves something more than the mere shifting of the axis of illumination of a headlight with respect to its normal zone of intense illumination and carries as its essential characteristic the simultaneous shifting of the focal axis of the light so that the zone of intense illumination is always maintained in focus however the axis of illumination may be varied. This is effected in the present invention by providing for a simultaneous shifting of the focal angle commensurate with the degree of variance of the axis of illumination from its normal plane. By the term "axis of illumination," as used herein, is meant the plane through the source of light perpendicular to the axis of the reflector.

The construction and operation of my invention will be more fully disclosed in

the specification which follows. In the drawings accompanying that specification I have shown a headlight which not only illustrates the principles involved but is in itself a form found satisfactory in practice.

Throughout specifications and drawings like reference numerals are correspondingly applied and in these drawings

Figure 1 is a central longitudinal section through a headlight in accordance with my invention showing in full and dotted lines two positions of the head light, and Fig. 2 is a view showing an automobile equipped with my headlights.

I have indicated at 1 the casing or shell of a headlight which is supported on suitable brackets 2 fixed to the body of an automobile 3. The shell 1 has a ring 4 secured to its open end and the ring has a continuously recessed rim 5 in which the lens 6 is fitted.

Within the casing 1 is mounted a suitable reflector shell 7. The shell 7 is shifted to vary the axis of illumination by a yoke shaped lever 8 extending through a slot 9 in the casing 1 and a suitable connection 10 fastened at one end to the lever 8 and terminating at its opposite end in conveniently operable position adjacent the driver's seat. The shifting movement of the reflector shell 7 is resisted by a coil spring 11 fastened to the lever 8 and to the shell 1. The spring 11 returns the reflector shell to original position when the connection 10 is released.

Slidably mounted in a bearing 12 set axially in the reflector shell 7 is a sleeve 13 carrying the usual contacts 14 for an incandescent bulb 15 screwed into said sleeve. One of the connections for the bulb 15 is indicated at 16. The rear end of the sleeve 13 is closed and is disposed as a vertical wall 17 adapted for sliding contact with a downwardly tapering cam surface 18 formed on the curved rear wall of the casing 1 above the focal axis of the headlight. The bulb 15 therefore moves with the movement of the reflector shell and as the wall 17 slides along the cam surface 18 the bulb 15 is moved outwardly against the resistance of a coil spring 19 confined about the sleeve 13 between the front wall of the bearing 12 and the closed end of the sleeve 13 to adjust its focal axis to the new axis of illumination.

tion. The spring 19 returns the sleeve 13 to original position upon return of the reflector shell to its original position.

In use when it is desired to shift the axis 5 of illumination, the connection 10 is drawn rearwardly to swing the reflector shell 7 forwardly and downwardly as indicated in dotted lines, Fig. 1, carrying the sleeve 13 and bulb 15 upwardly. The cam surface 18 10 causes the sleeve 13 to slide outwardly in its bearing 12 a distance proportionate to the degree of depression of the reflector shell to automatically adjust the focal axis to the new axis of illumination. This provides 15 for an intense illumination of the road immediately ahead of the car and relieves the driver of an approaching car of the objectionable glare. The means for shifting the reflector shell may obviously be varied if desired, as may be means for effecting a movement of the incandescent bulb proportionate to the angle of inclination of the reflector shell. These and various other modifications in the form and construction of my 20 device may obviously be resorted to if within the limits of the appended claims.

What I therefore claim and desire to secure by Letters Patent is:

1. In headlight equipment, a reflector 30 having a predetermined axis of illumination, a source of light associated with said reflector and having a normal focal axis coincident with said axis of illumination, and means for simultaneously varying both axes without destroying their coincidence.

2. In headlight equipment, a reflector having a predetermined axis of illumination, a source of light associated with said reflector and having a normal focal axis 40 coincident with said axis of illumination, means for simultaneously varying both axes without destroying their coincidence, and means for restoring both axes to their respective original positions.

3. In headlight equipment, a reflector having a predetermined axis of illumination, a source of light associated with said reflector and having a normal focal axis coincident with said axis of illumination, 50 means for shifting the axis of illumination and means for simultaneously shifting the focal axis to coincide with the new axis.

4. In headlight equipment, a reflector having a predetermined axis of illumination, 55 a source of light associated with said reflector and having a normal focal axis coincident with said axis of illumination, means for shifting the axis of illumination, means for simultaneously shifting the focal axis 60 to coincide with the new axis, and means for restoring both axes to their respective original positions.

5. In headlight equipment, a shiftable reflector having a predetermined axis of illumination, 65 a source of light associated with

said reflector and movable therewith, means for shifting the reflector to vary its axis of illumination, and means for simultaneously adjusting the focal axis to coincide with the new axis of illumination.

6. In headlight equipment, a shiftable reflector having a predetermined axis of illumination, a source of light axially mounted in said reflector and movable therewith, means for shifting the reflector to vary its axis of illumination, and means for simultaneously moving the source of light a distance proportionate to the degree of movement of the reflector to cause the focal axis to coincide with the new axis of illumination.

7. In headlight equipment, a shiftable reflector having a predetermined axis of illumination, a source of light reciprocally mounted in said reflector and movable therewith, means for shifting the reflector angularly to vary its axis of illumination, and a cam for simultaneously moving the source of light outwardly a distance proportionate to the degree of inclination of the reflector to cause its focal axis to coincide with the new axis of illumination.

8. In headlight equipment, a casing, a shiftable reflector therein having a predetermined axis of illumination, a source of light mounted in said reflector to move therewith, a carrier for said source of light, means for shifting said reflector to vary its axis of illumination, and means positioned for engagement with said carrier for simultaneously moving the same a distance corresponding to the degree of variation of the reflector to cause the focal axis of the source of light to coincide with the new axis of illumination of the reflector.

9. In headlight equipment, a casing, a shiftable reflector therein having a predetermined axis of illumination, a source of light reciprocally mounted in said reflector and moving therewith, a carrier for said source of light, means for shifting said reflector angularly to vary its axis of illumination, and means positioned for engagement with said carrier for simultaneously moving the same outwardly a distance corresponding to the degree of angular variation of the reflector to cause the focal axis of the source of light to coincide with the new axis of illumination of the reflector.

10. In headlight equipment, a casing, a shiftable reflector therein having a predetermined axis of illumination, a source of light reciprocally mounted in said reflector to move therewith and having a normal focal axis coincident with the axis of illumination, a carrier for said source of light, means for shifting said reflector angularly to vary its axis of illumination, a cam positioned for engagement with said carrier for simultaneously moving the same outwardly a distance

corresponding to the degree of angular variation of the reflector to cause the focal axis of the source of light to coincide with the new axis of illumination of the reflector, and means for restoring both the reflector and the source of light to their respective original positions.

11. In headlight equipment, a casing, a shiftable reflector therein having a predetermined axis of illumination, a sleeve movably mounted in said reflector and carrying a source of light having a focal axis normally coinciding with the axis of illumination of the reflector, means for shifting said reflector to vary its axis of illumination, means positioned for engagement with said sleeve to simultaneously move the source of light outwardly a distance corresponding to the degree of shifting movement of the reflector, to secure a new focal axis coincident with the new axis of illumination, and means for returning the sleeve to original position upon return of the reflector to original position.
12. In headlight equipment, a casing, a shiftable reflector therein having a predetermined axis of illumination, a sleeve movably mounted in said reflector and carrying a source of light having a focal axis normally coinciding with the axis of illumination of the reflector, means for shifting said reflector to vary its axis of illumination, a spring for returning said reflector to original position, means positioned for engagement with said sleeve to simultaneously move said source of light outwardly a distance corresponding to the degree of shifting movement of the reflector, to secure a new focal axis coincident with the new axis of illumination, and means for returning the sleeve to original position.
13. In headlight equipment, a casing, a shiftable reflector therein having a predetermined axis of illumination, a sleeve movably

mounted in said reflector and carrying a source of light having a focal axis normally coinciding with the axis of illumination of the reflector, means for shifting said reflector to vary its axis of illumination, a spring for returning said reflector to original position, a cam positioned for engagement with said sleeve to simultaneously move the source of light outwardly a distance corresponding to the degree of shifting movement of the reflector, to secure a new focal axis coincident with the new axis of illumination, and a spring for returning the sleeve to original position upon return of the reflector to original position.

14. In combination with a reflector having a predetermined axis of illumination, a source of light associated with said reflector and having a normal focal axis coincident with said axis of illumination, and means for varying the axis of illumination without destroying the coincidence of said axis with the focal axis of the light.

15. In combination, a tilting reflector and a source of light moving therewith, and means for automatically changing the focal axis of said source of light during the movement thereof.

16. In combination, a shiftable reflector having a predetermined axis of illumination and a source of light moving with said reflector and having its focal axis normally coinciding with the axis of illumination of the reflector in the normal position of the reflector and having a shifted focal axis coinciding with the new axis of illumination of the reflector when the reflector is shifted.

In testimony whereof I affix my signature in presence of two witnesses.

CHARLES R. C. BORDEN.
